Design for Font of Printing-Type

UNITED STATES PATENT OFFICE.

ANDREW LITTLE, OF NEW YORK, N. Y.

DESIGN FOR FONT OF PRINTING-TYPES.

Specification forming part of Design No. 8,379, dated June 8, 1875; application filed April 14, 1875.
[Term of Patent 14 years.]

To all whom it may concern:

Be it known that I, ANDREW LITTLE, of the city, county, and State of New York, have invented and produced a new and original Design for a Font of Printing-Type, of which the following is a specification:

The nature of my design is fully shown in the typographic impression accompanying this specification, to which reference is had;

and consists of a script letter formed as therein shown.

What I claim as new is—

The design for a font of printing-type, as shown.

ANDREW LITTLE.
